TOP BURNER IGNITION SYSTEM

John L. Lundgren, Rockford, Ill., assignor to Geo. D. Roper Corporation, Rockford, Ill., a corporation of Illinois

Application April 5, 1952, Serial No. 280,729

7 Claims. (Cl. 158—126)

This invention relates to an automatic ignition system for gas burners, and particularly to such a system for igniting the top burners on a gas stove.

It is an object of this invention to provide a novel ignition system for a gas burner in which an ignition pilot burner is lighted automatically in response to the opening of a shutoff valve for the main burner and in which the pilot burner remains lighted for a time interval following the extinguishing of the main burner.

It is also an object of this invention to provide a novel ignition system for a gas burner in which the gas supply to an ignition pilot burner is initially responsive to a shutoff valve for the main burner, and in which after the lighting of the pilot burner there is established an auxiliary gas supply to the pilot burner for maintaining the latter lighted for a time interval following the closing of the shutoff valve for the main burner.

Another object of this invention is to provide a novel ignition system for a gas burner in which the gas supply to an ignition pilot burner is under the control of a pressure responsive valve prior to the lighting of the pilot burner, and in which after the lighting of the pilot burner there is established a gas supply to the pilot burner which is independent of the pressure responsive valve.

A further object of this invention is to provide a novel ignition system for a gas burner which includes a pressure responsive valve in the gas supply line to the ignition pilot burner which opens in response to the supplying of gas to the main burner, and in which following the lighting of the pilot burner there is established an auxiliary gas supply to the pilot burner for maintaining a flame at the pilot burner independent of the pressure responsive valve for a time interval following the shutting off of the gas supply to the main burner.

A still further object of this invention is to provide a gas burner ignition system in which in the respective gas supply lines for the main burner and for an ignition pilot burner there is provided a pressure responsive valve which opens in response to the opening of a shutoff valve for the main burner to supply gas to the main burner and to the pilot burner, and in which after the pilot burner is ignited there is established a gas supply to the pilot burner which is independent of the pressure responsive valve for maintaining a flame at the pilot burner for a time interval following the closing of the shutoff valve for extinguishing the main burner.

Other and further objects and advantages of the invention will be apparent from the following description of a preferred embodiment thereof, which is shown schematically in the accompanying drawing for the purpose of illustrating the principles of this invention.

In the drawing:

The single figure is a schematic view of the gas burner ignition system of the present invention.

Referring to the drawing, the main burner 1 is here shown as being of conventional construction for use as a top burner on a gas stove, although the system of the present invention is not to be considered as being limited

to this particular type of gas burner. The main burner 1 receives its gas supply from a gas main 2, which communicates through a valve housing 3 with the manifold 4 leading to the mixer tube 5 for the main burner. A shutoff valve 6 of conventional design is located between the manifold 4 and the burner mixer 5 to provide the primary control for the gas supply to the main burner 1. Shutoff valve 6 is under the control of a conventional manually actuated control knob 7.

The secondary control means for the gas supply to the main burner 1 is provided by a pressure responsive flapper valve 8, which is located in the valve housing 3 between the gas main 2 and the manifold 4 leading to the main burner. Valve 8 is hinged on a pin 9, to which it is connected at its upper end, so that the valve 8 is normally biased by gravity to assume the position shown in the drawing. Valve 8 extends across the interior of the valve housing 3 and includes a metal plate 10 at its back side and a facing 11 of rubber or other resilient material at its inner side. As shown in the drawing, normally the pressure responsive valve 8 is seated against the valve seat 12 formed by the internal boss 13 in the valve housing 3. At this valve seat, the metal plate 10 at the back side of the pressure responsive valve 8 is cut away to permit the gas pressure at the back side of the valve to force the resilient facing 11 of the valve snugly against the valve seat 12. A bleed hole 45 extends through the flapper valve 8 to equalize the gas pressures on opposite sides of the valve when the shutoff valve 7 is closed.

The internal boss 13 in the valve housing 3 is formed with a gas passage 14 which leads from the valve seat 12. This valve passage 14 communicates with a conduit 15, which leads through a T-fitting 16 and conduit 17 to an ignition pilot burner 18. Thus, when the valve 8 is open (away from its seat 12) there is provided a gas supply for the pilot burner 18 which extends from the gas main 2, through the valve housing 3 past valve seat 12 into the gas passage 14, conduit 15, fitting 16, and conduit 17 to the pilot burner 18, which gas supply is arranged to maintain the pilot flame level above a predetermined minimum. Pilot burner 18 is in igniting relation, through a conventional horizontal flash tube 19, with the main burner 1. As indicated in dotted lines in the drawing, a fitting 20 and an auxiliary conduit 21 leading to another ignition pilot burner may be provided, in case it is desired to have the pressure responsive valve control more than one pilot burner on the stove.

The gas passage 14 also communicates with a chamber 22 in which is located a flexible, pressure responsive diaphragm 23, which carries a mobile switch contact 24 adapted to cooperate with a fixed contact 25. The mobile and fixed contacts 24, 25 are connected respectively to the conductors 26 and 27 of an electrical power circuit leading through a step-down transformer 28 from a plug 29 connected to a conventional source of 110-120 volt house current. Normally, with the valve 8 seated against valve seat 12 and consequently with no gas pressure in the chamber 22, the switch contacts 24 and 25 are spaced apart and the electrical power circuit is broken. However, when gas under pressure is supplied to the chamber 22 the switch formed by contacts 24 and 25 is closed, the power circuit is adapted to be completed through a normally closed switch 30, which is of the small, precision, snap-acting type, to the ignition coil 31 for the pilot burner 18 for lighting the gas issuing at the pilot burner.

Switch 30 is thermally responsive to the pilot burner 18 to open automatically following the lighting of the pilot burner for de-energizing the ignition coil 31. To this end, there is provided a bimetallic member 32 which carries a button 33 for operating the plunger 34 of

switch 30. The bimetal 32 is positioned to be responsive to heat from the pilot burner 18, and, except when heated sufficiently by the pilot burner, the bimetal 32 is located to maintain switch 30 in its normally closed condition. However, after the pilot burner 18 has been lighted and produces a flame level above said predetermined minimum due to its gas supply from conduit 15, the bimetal 32 responds to heat from the pilot burner flame to open switch 30 and thereby de-energize the ignition coil 31.

The bimetal 32 is also suitably operably connected (in the present instance through a linkage arm 35) to a normally closed valve 36. The latter is located in a valve housing 37 and is normally seated against its seat 38 to block communication between the inlet and outlet chambers 39 and 40 of the valve housing 37. The inlet chamber 39 communicates through a conduit 41 with an inlet passage 42, which communicates with the gas main 2 ahead of the pressure responsive valve. A conventional flow adjuster 43 in the conduit 41 limits the rate of flow of gas therethrough. The outlet chamber 40 in the valve housing 37 leads through an outlet conduit 44 to the fitting 16 leading to the pilot burner 18. Valve closure member 36 normally is seated. However, after the pilot burner 18 is lighted, the bimetal 32 responds to heat from the pilot burner and unseats the valve 36 to establish an auxiliary gas supply through conduits 41 and 44 to the pilot burner 18 which is independent of the pressure responsive valve 8.

In the operation of this system, initially the shut-off valve 6 is closed and the main burner 1 is extinguished; the gas pressure is equalized on opposite sides of the pressure responsive valve 8 and valve 8 is seated against the valve seat 12; pilot burner 18 is out; switch 24, 25 is open; switch 30 is closed; valve 36 is seated against its valve seat 38.

When the control knob 7 is turned to open the shut-off valve 6, this relieves the gas pressure at the back side of valve 8 and the resultant pressure unbalance moves valve 8 counterclockwise about its hinge axis 9. Gas from the gas main 2 flows through the valve housing 3, through manifold 4, valve 6 and mixer 5 to the main burner 1. Also, gas from the main 2 flows through the valve housing 3 past the valve seat 12 through passage 14, conduit 15, fitting 16 and conduit 17 to the pilot burner 18. At the same time gas pressure in the chamber 22 acting against the diaphragm 23 closes the mobile contact 24 against fixed contact 25 to complete the energization circuit for the ignition coil 31 (through normally closed switch 30). Ignition coil 31 lights the pilot burner 18, which in turn lights the main burner 1.

Following the lighting of the pilot burner 18, the pilot burner flame heats the thermal responsive bimetal 32 to open switch 30 and also to unseat valve 36. Opening of the switch 30 breaks the circuit to the ignition coil 31 to de-energize the latter. The unseating of valve 36 establishes an auxiliary gas supply through conduits 41 and 44 to the pilot burner 18.

When it is desired to extinguish the main burner 1 the manual control knob 7 is turned to close valve 6. This causes the pressure responsive valve 8 to return to its normal position seated against the valve seat 12 to cut off the primary flow of gas through conduit 15 to the pilot burner 18. However, the pilot burner continues to burn with a reduced flame due to the auxiliary gas supply through conduit 41, valve housing 37 and conduit 44, which auxiliary gas line is connected to the gas main 2 ahead of the pressure responsive valve 8. However, the flow restriction device 43 limits this auxiliary gas flow so that the level of this standby flame at the pilot burner 18 is insufficient to maintain the bimetal 32 in the condition to which it had been actuated by heat from the pilot burner after the latter was lighted. Therefore, after a time delay during which the bimetal 32 cools gradually, due to the lower flame at the pilot

burner 18, the bimetal 32 returns to substantially its original condition to seat valve 36 against its seat 38 to cut off the auxiliary gas supply to the pilot burner 18 for extinguishing the latter. Also, by this return movement of the bimetal 32 the switch 30 returns to its normally closed position, to condition the circuit for again energizing the ignition coil 31 when the main burner 1 is turned on the next time. The above-described auxiliary gas supply through conduit 41 to the pilot burner, 10 during the time required for switch 30 to re-close, is an operating precaution in the event that the operator should re-open valve 6 during this time interval. Should this occur, with the switch 30 open, the igniter 31 for the pilot burner would remain de-energized and the pilot burner would not ignite, in the absence of the above-described means for maintaining an auxiliary flame at pilot burner 18, so that there would be no provision for igniting the main burner 1 at this time.

Obviously, the principles of the present invention are 20 readily adaptable to an ignition system for a plurality of gas burners, such as a plurality of top burners on a gas stove, without departing from the spirit and scope of the present invention. Also, more than one pilot burner may be employed in the system and various ignition means for the pilot burner other than that described above may be adopted, within the spirit and scope of this invention. Also, various other modifications, omissions and refinements departing from the described form 25 of the invention may be adopted which do not depart from the spirit and scope of my invention.

I claim:

1. A gas burner ignition system comprising a gas supply line, a main gas burner, conduit means for supplying gas from said supply line to said main burner, a shut-off valve in said conduit means controlling the flow of gas to the main burner, a pilot burner in igniting relation to the main burner, pilot burner conduit means providing a predetermined gas supply from the supply line to said pilot burner to maintain a predetermined pilot flame level, 35 a pressure responsive valve in said pilot burner conduit means operative in response to the opening of said shut-off valve to open to supply gas to the pilot burner, a pilot burner ignition means for igniting said pilot burner in response to opening of said shutoff valve, an auxiliary pilot burner conduit leading to the pilot burner and connected to receive a gas supply from said supply line for providing an auxiliary gas supply to the pilot burner which is independent of the pressure responsive valve, a 40 normally closed valve in said auxiliary pilot burner conduit controlling the flow of gas therethrough, thermal responsive means positioned adjacent said pilot burner arranged to be actuated initial position to a displaced position in response to the heat produced by said predetermined flame level at the pilot burner and to return to said initial position when the pilot flame is below said predetermined level, said thermal responsive means operative upon actuation from said initial position to said displaced position to render said ignition means inoperative and operatively connected to said normally closed 45 valve to open the latter and maintain a gas supply through said auxiliary pilot burner conduit so long as said ignition means is rendered inoperative by said thermal responsive means, and flow restriction means in said auxiliary pilot burner conduit for maintaining the pilot burner flame produced by the flow of gas through said auxiliary conduit below said predetermined pilot flame level whereby said thermal responsive means is returned to said initial position at a time interval after said pressure responsive valve is closed.

2. A gas burner ignition system comprising a gas supply line, a main gas burner, conduit means for supplying gas from said supply line to said main burner, a shutoff valve in said conduit means controlling the flow of gas to the main burner, a pilot burner in igniting relation to the main burner, pilot burner conduit means providing a pre-

determined gas supply from said supply line to the pilot burner to maintain a predetermined flame level at the pilot burner, a pressure responsive valve in said pilot burner conduit means operative to open to supply gas to the pilot burner in response to the opening of said shutoff valve, means for igniting the pilot burner responsive to the opening of said shutoff valve, an auxiliary pilot burner conduit connected to said supply line and leading to the pilot burner, a normally closed valve in said auxiliary pilot burner conduit controlling the flow of gas therethrough, ignition control means actuatable from a normal position to a displaced position to render said pilot burner igniting means inoperative, and thermal responsive means controlling said ignition control means and operatively connected to said normally closed valve to control the opening and closing of the latter, said thermal responsive means being operative in response to heat from said predetermined pilot flame at the pilot burner after the ignition of the pilot burner to actuate said ignition control means and to open said normally closed valve to provide an auxiliary gas supply to the pilot burner which is independent of said pressure responsive valve and less than said predetermined gas supply, said auxiliary gas supply maintaining a reduced flame at said pilot burner while said pilot burner igniting means is maintained inoperative during a time interval following the closing of said pressure responsive valve, said reduced pilot burner flame provided by said auxiliary gas supply being insufficient to maintain said thermal responsive means operative whereby said ignition control means is returned to said normal position and said normally closed valve is closed a predetermined time interval after closing of said pressure responsive valve.

3. A gas burner ignition system comprising a gas supply line, a main gas burner, conduit means for supplying gas from the supply line to said main burner, a shutoff valve in said conduit means controlling the flow of gas to the main burner, a pilot burner in igniting relation to the main burner, means for igniting the pilot burner, pilot burner conduit means providing a gas supply from the supply line to the pilot burner, a pressure responsive valve in said pilot burner conduit means operative in response to the opening of said shutoff valve to supply gas to the pilot burner for ignition by said pilot burner igniting means, an auxiliary pilot burner conduit connected to said supply line and to the pilot burner for providing an auxiliary gas supply to the pilot burner, ignition control means actuatable from a normal position to a displaced position to render said igniting means inoperative, a normally closed valve in said auxiliary pilot burner conduit controlling the flow of gas therethrough, and thermal responsive means operative following the ignition of said pilot burner for actuating said ignition control means to render said pilot burner igniting means inoperative and for opening said normally closed valve to provide an auxiliary gas supply to the pilot burner which is independent of said pressure responsive valve to maintain a reduced level flame at said pilot burner for a time interval following the closing of said shutoff valve while said pilot burner igniting means is maintained inoperative, said thermal responsive means being operative after said time interval to permit closing of said normally closed valve and return of said ignition control means to said normal position.

4. A gas burner ignition system comprising a gas supply line, a main gas burner, conduit means providing a gas supply from the supply line to the main burner, a shutoff valve in said conduit means controlling the flow of gas to the main burner, a pilot burner in igniting relation to the main burner, pilot burner conduit means providing a gas supply from the supply line to the pilot burner, a pressure responsive valve in said pilot burner conduit means operative to open to supply gas to the pilot burner responsive to the opening of said shutoff valve, means for igniting the pilot burner responsive to the opening of said shutoff valve, an auxiliary pilot burn-

er conduit leading to the pilot burner and connected to said supply line for providing an auxiliary gas supply to the pilot burner, a normally closed valve in said auxiliary pilot burner conduit, and thermal responsive means controlling said pilot burner igniting means and operatively connected to said normally closed valve and positioned to be responsive to heat from the pilot burner, said thermal responsive means being operative in response to heat from the pilot burner after the latter is ignited to render inoperative said pilot burner igniting means and to open said normally closed valve to establish an auxiliary gas supply to the pilot burner which is independent of said pressure responsive valve, said thermal responsive means being operative to maintain said pilot burner igniting means inoperative and to maintain open said normally closed valve a time interval following the closing of said pressure responsive valve, said auxiliary pilot burner conduit during said time interval supplying gas through said normally closed valve to the pilot burner and maintaining a flame at the pilot burner which is insufficient to maintain said thermal responsive means operative to hold open said normally closed valve and also insufficient to maintain said pilot burner igniting means inoperative.

5. A gas burner ignition system comprising a gas supply line, a main gas burner, a pilot burner in igniting relation to the main burner, conduit means providing a gas supply from the supply line to the main burner, a shutoff valve in said conduit means controlling the flow of gas to the main burner, a pressure responsive valve in said conduit means between said shutoff valve and said supply line, said pressure responsive valve including a member positioned in said conduit means and movable between opened and closed positions, said member when in its closed position extending completely across said conduit means so that no gas may flow past the member, a pilot burner conduit for supplying gas to the pilot burner connected to said pressure responsive valve to have its gas supply under the control thereof, said pressure responsive valve being operative in response to the pressure differential at the opposite sides of said member resulting from the opening of said shutoff valve to move to its open position and permit gas to flow through said conduit means to the main burner and through the pilot burner conduit to the pilot burner and being operative to close when said main shutoff valve is closed, and means for igniting the pilot burner when gas is supplied thereto.

6. A gas burner ignition system comprising a gas supply line, a main gas burner, main burner conduit means providing a gas supply from the supply line to the main burner, a shutoff valve in said main burner conduit means controlling the flow of gas to the main burner, a pilot burner in igniting relation to the main burner, pilot burner conduit means providing a gas supply for the pilot burner, a pressure responsive valve in said pilot burner conduit means controlling the flow of gas therethrough, said pressure responsive valve including a member disposed in said main burner conduit means between said shutoff valve and said supply line and movable between opened and closed positions therein, said member when in the closed position thereof extending completely across said main burner conduit means so that no gas may flow through said conduit means past said member, said pressure responsive valve being operative in response to the pressure differential on opposite sides of said member resulting from the opening of said shutoff valve to move to its open position and permit gas to flow through the main burner conduit means to the main burner and through the pilot burner conduit means to the pilot burner, means responsive to opening of said shutoff valve for igniting the pilot burner, an auxiliary pilot burner conduit leading to the pilot burner and communicating with said supply line, a normally closed valve in said auxiliary pilot burner conduit controlling the flow of gas therethrough, ignition control means actuatable from a normal position

to render said igniting means inoperative, and thermal responsive means operatively connected to said ignition control means and to said normally closed valve and positioned to be responsive to heat from the pilot burner, said thermal responsive means being operative in response to heat from the pilot burner to actuate said ignition control means and thereby render said pilot burner igniting means inoperative and to open said normally closed valve to establish an auxiliary gas supply to the pilot burner which is independent of said pressure responsive valve to maintain a flame at the pilot burner while said pilot burner igniting means is maintained inoperative by said thermal responsive means, said thermal responsive means being operative after a time delay following the closing of said pressure responsive valve to return said ignition control means to said normal position and to close said normally closed valve to extinguish the pilot burner.

7. A gas burner ignition system comprising a main gas burner, conduit means for supplying gas to the main burner, a main burner shutoff valve in said conduit means controlling the flow of gas to the main burner, a pilot burner in igniting relation to the main burner and operative to receive a gas supply from said conduit means when said main burner shutoff valve is opened, an electric igniter in igniting relation to the pilot burner, a pressure responsive switch controlling the energization of said igniter operative to close to complete the energization circuit for said igniter in response to gas pressure following the opening of said shutoff valve, an auxiliary pilot burner conduit leading to the pilot burner and connected to said conduit means to supply gas to the pilot burner independent of said shutoff valve, a normally closed auxiliary

pilot burner valve in said auxiliary pilot burner conduit, thermal responsive means operatively connected to said auxiliary pilot burner valve and responsive to heat from the flame in the pilot burner, and a normally closed switch controlling said igniter and controlled by said thermal responsive means, said thermal responsive means being operative in response to lighting of the pilot burner to open said normally closed switch to de-energize the igniter and to open said auxiliary pilot burner valve to provide an auxiliary gas supply to the pilot burner which is independent of said main burner valve, said thermal responsive means being operative to maintain said auxiliary pilot burner valve open for a time interval following the closing of said main burner shutoff valve and while said igniter remains de-energized by said thermal responsive means, said auxiliary pilot burner valve while open following the closing of said main burner shutoff valve maintaining a flame at said pilot burner which is insufficient to maintain said thermal responsive means operative to retain said normally closed switch open after said time interval.
